FIG. 5

FIG. 4

FIG. 3

UNITED STATES PATENT OFFICE.

ERNEST W. PAULSON, OF OTO, IOWA.

PLOW.

1,358,460.

Specification of Letters Patent.

Patented Nov. 9, 1920.

Application filed March 9, 1918. Serial No. 221,419.

To all whom it may concern:

Be it known that I, ERNEST W. PAULSON, a citizen of the United States, and a resident of Oto, in the county of Woodbury and State of Iowa, have invented new and useful improvements in Plows, of which the following is a specification.

The present invention relates to plows. The invention aims primarily to provide a plow embodying certain novel features of construction particularly adapting the device for use on side hills.

Another object of the invention is the production of a plow embodying certain novel features of construction adapted more particularly for a cultivator, and which operate to neutralize the tendency of the machine to creep on a side hill.

A further advantage of the invention resides in the fact that the machine may be instantly shifted laterally in either direction to follow crooked rows.

Furthermore, the invention contemplates an improved cultivator, inexpensive and simple in construction, yet thoroughly efficient in operation.

With these and other objects in view the invention, consisting in the construction, combination and novel arrangement of parts, will be fully understood from the following description, reference being had to the accompanying drawings, which form a part of this application and in which like characters of reference indicate corresponding parts throughout the several views, of which—

Figure 1 is a plan of a cultivator constructed in accordance with the invention; Fig. 2 is a vertical section of the same taken on the line 2—2 of Fig. 1; Fig. 3 is a fragmentary rear elevation of the same; Fig. 4 is an enlarged perspective view of the controlling mechanism and of the parts associated therewith; and Fig. 5 is a perspective view of one of the axle bearings and associated parts.

Although I have illustrated and herein-after describe the preferred embodiment of the invention, I would not be understood as being limited to the specific structure chosen for illustration, for various alterations and modifications may be made in the details of construction and arrangement of parts without departing from the spirit and scope of the invention as defined in the appended claims.

Referring now to the illustrations, the device consists of a main frame, including preferably an arched axle comprised of parallel channel irons, 6, the arms of which decline outwardly as at 7, and a front cross member, 8, preferably T-shaped in cross section and connected with the axle by bars, 9. Upon the bars 9 are mounted segmental plates 10, upon which are pivoted draft tongues, 11. At the ends of the axle are upright shafts 12, rotatably mounted in bearings mounted to oscillate between the axle arms; these bearings preferably consist of collars, 13, which freely encircle the shafts, 12, and are provided with pintles, 14, journaled in openings in the arms of the axle. Said bearings rest on spindles, 15, extending laterally from the shafts, 12, and on which the travel wheels, 16, rotate. Between the axle members, 6, is positioned a shaft, 17, slidable longitudinally in bearings, 18, carried by the axle members. The ends of the shaft, 17, are provided with eyes, 19, which freely encircle the upper ends of the shafts, 12. The shafts, 12, are provided with crank arms, 20, connected by pitmen, 21, with arms, 22, mounted on the rear axle member.

By virtue of the structure now disclosed it is evident that longitudinal movement of the shaft, 17, will direct the wheels at an angle to the direction of travel, and also tilt them vertically, as shown in dotted lines in Figs. 1 and 3. The device illustrated is a two row cultivator and is provided with four gangs of plows, each consisting of a pair of plow beams, 23, carrying at their rear ends the shovels or plows proper, 24, and the forward ends of the beams are pivoted on the lower ends of supporting rods, 25, which pivotally depend from bearings, 26, mounted to slide longitudinally on the cross member, 8. In the present embodiment these bearings, 26, consist of elongated blocks which slide adjacent the lower edge of said cross member and are provided with overturned flanges, 27, which engage the upper sides of the flanges of the cross member. The gangs are connected in pairs whereby lateral movement of one gang imparts corresponding movement to the companion pair. For this purpose the bearings, 26, are provided with forwardly extending flanges, 28, the said flange of each block being detachably interconnected with the flange of the adjacent companion bearing by

a bar, 29, bolted or otherwise secured to the flange, as at 30. The flanges are provided with a plurality of openings, 31, to receive the bolts 30, whereby the distances between the gangs may be altered to correspond with the spaces between the corn rows. Each gang is connected with its mate by means of an intermediate yoke, 32, the arms of which are mounted in bearings, 33, 5 mounted on the beams, and the web of which is formed with a knuckle, 34, whereby the yoke may be spread or contracted. On the shaft, 17, are pivoted bars, 35, which decline forwardly and have their lower ends pivoted, as at 36, to the beams, whereby the bars, 35 and 25, co-act as the machine moves forwardly to depress the shovels, from which it is obvious that the greater the resistance of the earth on the shovels the greater will 15 be the downward pressure. This feature is not a part of the present invention but forms the subject-matter of my co-pending application, Serial No. 221,418, filed Mar. 9, 1918.

The machine is provided with a driver's 20 seat, 37, suitably supported by the main frame.

The controlling mechanism consists of a shaft, 38, journaled in bearings, 39 and 40, mounted, respectively, on the rear axle member and front cross member. On the said shaft is mounted a crank arm, 41, connected by a pitman with an arm, 43, mounted on the shaft, 17. Adjacent to its front end the shaft, 38, carries a crank arm, 44, connected 35 by pitmen, 45, with the adjacent bearings, 26. The shaft, 38, also carries a crank arm, 46, connected by pitmen, 47, with the rear ends of the draft tongues. The shaft, 38, extends a distance rearwardly from the axle 40 and is provided with oppositely disposed crank arms, 48, which form handle bars positioned on opposite sides of the driver's seat.

It is now evident that by turning the 45 handle bars at an angle as shown in Fig. 3, the shaft, 38, will be operated to shift the tongues at an angle to the main frame and the main frame will be shifted laterally by the movement of the shaft, 17, since the 50 travel wheels tilt on their lower peripheries. Obviously the shaft, 17, moves relatively farther than the main frame, which causes the tilting movement and causes one side of the frame to raise and the other to lower 55 according to the direction of tilting. The mechanism may be locked in any desired position by means of a detent controlled by the driver and engageable with a quadrant mounted on the main frame. In the present embodiment, therefore, I provide a pawl 60 in the shape of a bell crank, 49, fulcrumed as at 50, between uprights, 51, secured to the shaft, 38. One arm of the bell crank is engageable with a toothed quadrant, 52, which 65 may be formed integrally with the bearing,

39; and the depending arm is pivoted to the forward end of a rod, 53, slideable in a bearing, 54, mounted on the rod, 38. The rear end of the rod, 53, is provided with a cross head, 55, between which and the bearing, 54, 70 is interposed a compression spring, 56, which serves to hold the pawl in yieldable engagement with the quadrant. On the laterally disposed portions of the handle bars, 48, are fulcrumed levers, 57, the adjacent ends of 75 which engage the head of the rod, 55, and the remote ends of which are connected by links, 58, with grips, 59, on the rear of the handle bars. It is now clear that from either handle bar the operator can instantly 80 control the detent.

I also provide improved means by which the driver can move the pairs of gangs toward or from each other. This means consists of short upright shafts, 60, journaled 85 in bearings, 61, mounted on the beams adjacent the driver's seat, the said shafts being provided with crank arms, 62, interconnected by a rod, 63. The upper ends of the said shafts are provided with cross members, 64, suitably formed for engagement by the driver's feet. By forcing the adjacent ends of cross members, 64, forwardly the pairs of gangs will accordingly be forced each toward the other, while forward movement of the 95 remote ends of the cross members, 64, will force the pairs of gangs each toward the other.

Having thus described my invention, what I claim as new, and desire to secure by Letters Patent of the United States, is,—

1. An implement comprising a frame, upright shafts at opposite sides thereof, bearings in which the shafts are journaled, said bearings being pivoted to the frame to oscillate vertically, lateral spindles on the shafts, travel wheels rotatable on the spindles, and means for tilting and turning the shafts to thereby tilt and direct the wheels at an angle to the direction of travel.

2. An implement including a frame, upright shafts on opposite sides thereof, bearings on the lower portions of the shafts, lateral spindles on the lower ends of the shafts, travel wheels rotatable thereon, the bearings being pivoted to the frame to oscillate in vertical planes transversely of the frame, whereby the shafts may be swung outwardly or inwardly to tilt the wheels on their lower peripheries, and means for simultaneously 120 swinging the shafts in like directions.

3. An implement including a frame, upright shafts on opposite sides thereof, bearings on the lower portions of the shafts, lateral spindles on the lower ends of the shafts, 125 travel wheels rotatable thereon, the bearings being pivoted to the frame to oscillate in vertical planes transversely of the frame, whereby the shafts may be swung outwardly or inwardly to tilt the wheels on their lower 130

peripheries, a shaft interconnecting the upper ends of the shafts and means for shifting the shaft longitudinally.

4. An implement including a frame, upright shafts on opposite sides thereof, bearings in which the lower portions of the shafts are journaled, lateral spindles on the lower ends of the shafts, travel wheels rotatable thereon, the bearings being pivoted to the frame to oscillate in vertical planes transversely of the frame, whereby the shafts may be swung outwardly or inwardly to tilt the wheels on their lower peripheries, crank arms on the upper portions of the shafts, links between the crank arms and frame, whereby the shafts will be turned to direct the wheels at an angle to the direction of travel when the shafts are swung outwardly or inwardly, a rock shaft disposed longitudinally of the frame, a crank arm thereon, a connection between said crank arm and the upper ends of the upright shafts, and means for controlling the rock shaft.

5. An implement including a frame, upright shafts on opposite sides thereof, bearings in which the lower portions of the shafts are journaled, lateral spindles on the lower ends of the shafts, travel wheels rotatable thereon, the bearings being pivoted to the frame to oscillate in vertical planes transversely of the frame, whereby the shafts may be swung outwardly or inwardly to tilt the wheels on their lower peripheries,

crank arms on the upper portions of the shafts, links between the crank arms and frame, whereby the shafts will be turned to direct the wheels at an angle to the direction of travel when the shafts are swung outwardly or inwardly, a rock shaft disposed longitudinally of the frame, a crank arm thereon, a connection between said crank arm and the upper ends of the upright shafts, and means for controlling the rock shaft.

6. An implement including a frame, upright shafts on opposite sides thereof, bearings on the lower portions of the shafts, lateral spindles on the lower ends of the shafts, travel wheels rotatable thereon, the bearings being pivoted to the frame to oscillate in vertical planes transversely of the frame, whereby the shafts may be swung outwardly or inwardly to tilt the wheels on their lower peripheries, a rock shaft disposed longitudinally of the frame, a crank arm thereon, connections between the crank arm and the upper ends of the upright shafts, and means for controlling the rock shaft.

In testimony whereof, I have hereunto set my hand this 6th day of March, 1918.

ERNEST W. PAULSON.
